ABSTRACT

A margin signal for typewriters is disclosed comprising a plurality of frame supported resonating elements that cooperate with a plurality of frame supported hammer members and are acted upon by an actuating means supported on a movable carriage. As the carriage traverses, the actuating means trips the hammer members in sequence which sequentially impact on the resonating elements thereby effecting a plurality of sequential audible signals of varied modulation to indicate to the operator that the end of line-of-write is approaching.

DUAL TONE MARGIN SIGNAL FOR
TYPEWRITERS

BACKGROUND OF THE INVENTION

This invention relates to typewriters and more particularly to margin signals for indicating that the end of line-of-write of a typewritten sheet is approaching.

Desirable features of margin signals for typewriters are audibility, compact design, and resonance, and to a great extent these requirements have been met. However, present margin signals in typewriters are deficient in that most typewriters have a single emitted signal for indicating the approach of the end of line-of-write. Consequently, in many areas, a noisy environment would make it difficult to hear the signal. Furthermore, in most offices, the signal emitted would be similar to other sounds and signals in the area where many business machines may be located and it may be difficult to easily differentiate between the margin signal and the surrounding signals.

Other margin signals utilize visual signals that are primarily designed for persons with hearing deficiencies. It would be a distraction for a typist without a hearing deficiency, who normally only views the written material that she is typing and who rarely looks at the character keys on the sheet being typed to draw her attention to a margin signal light.

SUMMARY OF THE INVENTION

The present invention provides a dual tone signalling device for typewriters and includes a pair of co-axially mounted resonating elements in a telescopic relationship and a pair of cooperating hammer elements, both of which are horizontally supported on a frame. The hammer elements are sequentially actuated by an actuating means supported on a margin stop that is slideably mounted on a movable paper supporting carriage. The actuated hammer elements sequentially impact the resonating elements whereby a plurality of sequential audible signals is produced to indicate to the operator that the end of a line-of-write is approaching.

Accordingly, an object of the present invention is to provide a margin signalling means for a typewriter that emits a plurality of tones in sequence and of a modulation substantially different from the tone emitted by conventional typewriter signals, such as a bell.

A further object of the present invention is to provide a margin signalling means for a typewriter that emits a plurality of tones of different modulation.

A still further object of the present invention is to provide a margin signalling means for typewriters that emits a plurality of tones in sequence wherein the time between signal tones and the end of line-of-write may be varied.

Other objects, features, and advantages of the invention will become more apparent from the following description, appended claims and accompanying drawing.

BRIEF DESCRIPTION OF THE DRAWING

The DRAWING is a perspective view of the front of a typewriter showing the margin signal mechanism.

DESCRIPTION OF THE PREFERRED
EMBODIMENT

Referring now to the drawing where one part of the embodiment is supported on a typewriter frame 12 and cooperates with a second part supported on a movable

carriage 13 that is mounted for reciprocating movement on the frame 12.

The margin signal device includes a first tubular resonating element 9 horizontally fixed against frame 12 at its closed end 14. A second tubular resonating element 10 is co-axially supported within, and in contact at its closed end 15 with, resonating element 9. Element 10, of different modulation, is of lesser diameter but of greater length than element 9 so that an open end 18 of element 10 extends beyond an open end 11 of element 9.

A pair of L-shaped hammer bellcranks 20 and 22 are pivotally supported about a common pivot 24 on frame 12 and independently biased in a clockwise direction by frame supported extension springs 26 and 28. A pair of integral actuating arms 30 and 32 of hammer bellcranks 20 and 22 having sloped ends extend upwards from pivot 24 and are of unequal lengths to permit sequential actuation by an actuating means to effect a plurality of sequential audible signals.

Extending laterally from pivot 24 are thin flexible arms 34 and 36 of bellcranks 20 and 22 that terminate in downward extending hammer members 38 and 40. Hammer members 38 and 40 are at rest when aligned immediately above and spaced from resonating elements 9 and 10 respectively and supported in their rest position by arms 34 and 36 resting on a frame extension abutment 42.

A bellcrank 44 is pivotally supported about a pivot 30 46 on a conventional margin stop bracket 48 slideably supported on a margin rack 50 that is rigidly mounted on movable carriage 13. Bellcrank 44 includes an upper extension 52 and a lower extension 54 having an upper slot 56 and a lower slot 58 at their respective ends.

A margin stop 49 projects down from margin stop bracket 48 with its path of traverse in alignment with a fixed carriage stop 47. Therefore, when the margin stop bracket 48 is adjusted to a desired position on margin rack 50 and the carriage 13 traverses the frame 12, margin stop 49 abuts carriage stop 47, at which time further movement of carriage 13 is arrested thereby determining the end of line-of-write.

An actuator 60 is pivotally supported on bellcrank 44 off center of its length about a pivot 62 which is slideable within slot 58 of bellcrank 44. The ends of actuator 60 terminate in an actuator tab 64 and a stop tab 66 that abuts the underside of margin stop bracket 48 and a lateral portion 67 that abuts a forward extension 68 of margin stop bracket 48 to limit the counterclockwise rotation of actuator 60.

An adjustment lever 70 is pivotally supported on the underside of a control knob 72 and contoured to include an upstanding tab 74 and a tab 76 which projects 55 through slot 56 of upper extension 52.

During typewriter operation, carriage movement occurs each time a keybutton (not shown) is depressed to print a desired character, whereupon, through linkage, a carriage coupled escapement mechanism (not shown) is disengaged to allow the carriage 13 to move longitudinally from right to left a predetermined distance.

In the present invention, margin stop bracket 48 is 60 manually adjusted to a position on carriage rack 50 corresponding to the desired right hand margin setting. As typing continues, the carriage 13 moves progressively leftwards until actuator tab 64 engages actuating

arms 30 and 32. Consequently, hammer bellcranks 20 and 22 are pivoted counterclockwise about pivot 24 thereby raising hammer bellcranks 20 and 22 out of contact with frame abutment 42 to a striking position. As carriage 13 continues its lateral movement, actuator tab 64 slideably and sequentially disengages from hammer bellcrank actuating arms 30 and 32. As a result, hammer bellcranks 20 and 22 are sequentially released from their firing position and arms 34 and 36 sequentially contact frame abutment 42 and then deflect 10 downward about frame abutment 42 due to the inertia of the hammer members 38 and 40 and the flexibility of arms 34 and 36 to sequentially strike resonating elements 9 and 10 to effect sequential audible signals of variable modulation indicating that the end of a line-of-write is approaching. Hammer bellcranks 20 and 22 then relax to the rest position on frame abutment 42 whereby hammer members 38 and 40 are again in spaced relationship with resonating elements 9 and 10. 15

Actuating arms 30 and 32 extend upwards into the 20 path of travel of actuator tab 64 so as carriage 13 is returned to its extreme right position for subsequent typing, actuator tab 64 abuts arms 30 and 32 and is deflected to pivot clockwise about pivot 62 until arms 30 and 32 slide free of actuator tab 64. Adjustment of the 25 distance between the sequential signals and the end of line-of-write is accomplished by manually pivoting adjustment control lever 70 clockwise or counterclockwise to pivot bellcrank 44 and urge actuator 60 laterally. The lateral movement of actuator 60 varies the 30 distance between tab 64 and margin stop 49 which in turn varies the distance between the sequential signals and the end of line-of-write. 35

Consequently, the distance between the sequence of signals and the end of line-of-write will be varied.

While the foregoing description has shown and described the fundamental novel features as applied to a preferred embodiment, it will be understood by those skilled in the art that modifications embodied in various forms may be made without departing from the 40 spirit and scope of the invention.

What is claimed is:

1. An audible signal mechanism for indicating the end of a line-of-write in a typewriter having a frame including an abutment and a carriage supported on the 45 frame and movable relative to the frame, a carriage rack fixed on the movable carriage and a margin stop adjustably supported on the carriage and movable relative to the carriage comprising:

an actuator assembly pivotally supported about a first pivot on the margin stop including an adjustment lever pivotally supported on a knob of the margin stop and an adjustable actuator coupled to said ad-

justment lever by a motion transmitting means therebetween; a pair of L-shaped actuatable members pivotally supported about a second pivot on the frame comprising, a plurality of rigid arms extending upwards of said second pivot into the path of said actuator for engagement and disengagement by said actuator when said actuator traverses the frame, a plurality of flexible arms terminating in a plurality of hammer members and extending laterally of said second pivot for contacting the frame abutment and deflecting beyond the frame abutment when said rigid arms are engaged and disengaged by said actuator; and

a first resonating element horizontally supported on the frame and a second resonating element coaxially supported within said first resonating element with a portion of said second resonating element projecting from said first resonating element, said resonating elements positioned below said hammer members for sequentially striking by said hammer members for effecting a plurality of sequential audible signals for indicating the end of line-of-write.

2. An audible signal mechanism for indicating the end of a line-of-write in a typewriter having a frame including an abutment and a carriage supported on the frame and movable relative to the frame, a carriage rack fixed on the movable carriage and a margin stop adjustably supported on the carriage and movable relative to the carriage comprising:

actuating means pivotally supported on the margin stop and adjustable relative to the margin stop; a pair of actuatable members pivotally supported on the frame, said actuatable members having rigid portions extending into the path of said actuating means in staggered relationship for engagement and disengagement by said actuating means when the carriage traverses the frame and flexible portions extending laterally for contacting the frame abutment and deflecting beyond the frame abutment when said rigid portions are engaged and disengaged by said actuating means; and

a pair of resonating elements laterally supported on the frame for sequentially striking by said flexible portions for effecting a plurality of sequential audible signals for indicating the end of line-of-write.

3. An audible signal mechanism as defined in claim 2 wherein said actuating means is laterally adjustable for sequentially engaging said actuatable members when the carriage traverses the frame.
